UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PANEL BOARD.

Application filed June 14, 1920. Serial No. 388,828.

To all whom it may concern:

Be it known that I, REUBEN B. BENJAMIN, a citizen of the United States, residing at Chicago, in the county of Cook and State of Illinois, have invented new and useful Improvements in Panel Boards, of which the following is a full, clear, concise, and exact description, reference being had to the accompanying drawing, forming a part of this specification.

My invention relates to panel-boards and containers for the same, having particular relation to devices, of the character designated, adapted for use in residences or other small buildings, and has for its object to provide a panel-board which shall be composed of interchangeable and standard base sections and which shall embody a minimum number of parts in its construction.

For a better understanding of my invention reference may be had to the accompanying drawings in which;

Fig. 1 is a plan view of a panel-board and container embodying my invention;

Fig. 2 is an elevational, sectional view taken on the line 2—2 of Fig. 1; and

Fig. 3 is a top plan view of an interchangeable, standard base member employed in my invention.

One object of my invention is to provide an insulating base section which shall have receptacles and switching means together with bus-bars so associated therewith, that a number of said sections may be embodied in a panel-board and thereby provide for a derivation of any desired number, within limits, of branch circuits from said board. In the attainment of this object I so construct the elements employed and so embody them in the base sections that a minimum number of parts is necessary.

Another object of my invention is to provide a cap portion for the aforesaid base section which is apertured to receive the receptacles and other devices mounted upon the base section in such manner that a dead-front panel-board is constituted, although easy access may be had to said receptacles, as well as to whatever switching means may be associated with said base.

A still further object of my invention is to so form the interfitting base and cap portions of the panel-board and to so position the same within a hinged-cover casing that an ample wiring gutter is formed between

the insulating base and cap portions and the outer portions of said casing.

Referring now more particularly to the drawings, a panel-board casing comprises a dish portion 1 provided with a flanged edge 2, to which is secured a cover 3, the latter having an apertured portion which is adapted to be closed by a hinged member 4. Disposed within the casing and substantially under the closure member 4 are base and cap members 5 and 6 respectively, comprising together, with their associated devices, a dead-front panel-board. The cap member 6 has formed integrally therewith a peripheral barrier 7 which extends upwardly to meet the cover 3 of the casing in such manner that it assists in forming a wiring gutter 8 between the outer dish portion of the casing and the panel board proper.

Referring now to Fig. 3, the insulating base 5 has associated therewith bus-bars 9, 10 and 11 which are notched, as shown, to cooperate with interfitting screws 12, whereby any desired number of base sections may be electrically connected. As illustrated, two branch circuits 13 and 14 are derived from the base section 5, and receptacles whereby fuses may be positioned in each lead of each circuit are also associated with said base.

Receptacles 15 and 16, each comprising center contacts 17 and shell contacts 18, are associated with what may be assumed to be return leads 19 and 20 of the circuits 13 and 14 respectively. Receptacles 21—21, each comprising center contacts 22 and shell contacts 23, are associated with the other leads 24 and 25 of the circuits 13 and 14, respectively.

It will be observed that the center contacts 17—17 of the receptacles associated with the bus-bar 10 are formed integrally with the latter. The center contacts 22—22 of the receptacles associated with the outside bus-bars 9 and 11 comprise integral portions of conducting members 26, the other ends of which are struck upwardly to constitute poles 27—27 for switching means 28. The latter comprises conducting engaging clips 29 and 30 which are electrically connected at one end, and which are placed in and out of contact with the pole 27 and another pole 31 by means of an insulating handle member 32. The latter may be moved in a specially formed slot in the cap portion 6 as

2
shown, whereby when the latter is interfit-
ted with the insulating base 5 no live parts
of the switch are accessible. The pole 31
comprises an integral portion of a conduct-
5 ing member 33 which is connected to the
bus-bar 11. The cap 6 is, of course, aper-
tured to receive the shell contacts and recep-
tacles, as shown, and the apertures are so
formed therein that a dead-front panel-
10 board is formed. Moreover, the integral
barrier 7 meets the cover 3 of the casing in
such manner that a wiring gutter is formed
in said casing.

In order to identify the related circuits
15 and switches I find it advantageous to place
designating means on the top of the cap por-
tion as shown at 34, whereby the various
branch circuits and their associated
switches may be identified. A considera-
20 tion of Fig. 1 will illustrate the neat and com-
pact manner in which a device embodying
my invention may be constructed, the man-
ner in which the cap portion is apertured to
receive the receptacles and the branch cir-
25 cuit switches being clearly shown therein.

While I have illustrated one cap portion
as functioning with two base sections it is
obvious that it is not always necessary for
this relation to hold. Where a number of
30 base sections are employed it may be found
advantageous to make standard caps there-
for and to supply additional cap portions
having barriers so formed that a composite
panel-board in which the barrier 7 will be
35 peripherally continuous may be built up of
a number of base sections and a number of
cap portions.

While I have shown but one embodiment
40 of my invention it is apparent that many
modifications therein may occur to those
skilled in the art and I desire, therefore,
that my invention be limited only by the
showing of the prior art or by the scope of
45 the appended claims.

Having thus described my invention,
what I claim as new and desire to secure by
Letters Patent is:

50 1. In a panel-board, interchangeable insu-
lating bases, buses associated therewith, re-
ceptacles mounted thereupon, some of said
receptacles having as their center contacts
portions of one of said buses, and the center
55 contacts of the other receptacles being con-
nected to the other buses through switching
elements.

60 2. In a panel-board, interchangeable insu-
lating bases, buses associated therewith, re-
ceptacles mounted thereupon, some of said
receptacles having as their center contact
portions of one of said buses, switches like-
65 wise mounted on said base, and means con-
stituting the center contacts of the other re-
ceptacles and one pole of said switches.

65 3. In a panel-board, interchangeable insu-
lating bases, buses associated therewith, re-

ceptacles mounted thereupon, some of said
receptacles having as their center contact
portions of one of said buses, switches like-
70 wise mounted on said base, and conducting
members shaped at one end to form center
contacts for the other receptacles and hav-
ing an L-portion at the other end to form
one pole of said switches.

4. In a panel-board, interchangeable insu-
lating bases, substantially parallel buses ar-
ranged medially thereof, receptacles having
75 shell contacts mounted on said bases, por-
tions of one of said buses forming the center
contacts of some of said receptacles, and the
other buses being connected to the other re-
ceptacles through switches, and means in-
80 cluding wiring terminals for permitting the
connection of the shell contacts of said re-
ceptacles to branch circuits, as desired.

5. In a panel-board, interchangeable in-
sulating bases, substantially parallel buses
arranged medially thereof, receptacles hav-
85 ing center and shell contacts mounted on
said bases, portions of one of said buses
forming the center contacts of some of said
receptacles and the other buses being con-
nected to the other receptacles through
90 switches, and an insulating cap apertured
to receive said receptacles and said switches,
the base and cap being so formed and so
interfitting that channels are formed to per-
mit of the connection of said shell contacts
95 to branch circuits, as desired.

6. In a panel-board, interchangeable insu-
lating bases, substantially parallel buses
arranged medially thereof, receptacles hav-
100 ing center and shell contacts mounted on
said bases, the central bus providing center
contacts for certain of said receptacles,
others of said receptacles being adapted for
connection to the outside buses, and switches
105 mounted on said base for connecting said
outside buses to the center contacts of the
appropriate receptacles.

7. In a panel-board, interchangeable in-
sulating bases, substantially parallel buses
arranged medially thereof, receptacles hav-
110 ing center contacts and shell contacts mount-
ed on said bases, the central bus being
formed to provide center contacts for cer-
tain of said receptacles, others of said re-
ceptacles being adapted for connection to
115 the outside buses, switches mounted on said
bases for connecting said outside buses to
the center contacts of the correct receptacles,
integral members constituting the center
contacts of said outside receptacles and one
120 pole of said switches, and integral members
contacting with said outside buses and
forming the other pole of said switches.

125 8. An interchangeable panel-board section
adapted for the derivation of two branch
circuits therefrom comprising an insulating
base, substantially parallel buses associated
with said base, two receptacles associated
130

with the middle bus, portions of the latter being shaped to form center contacts for said receptacles, two receptacles, one adapted to be associated with each of the outside buses, and switches to connect said latter receptacles to their associated buses.

9. An interchangeable panel-board section adapted for the derivation of two branch circuits therefrom comprising an insulating base, substantially parallel buses associated with said base, two receptacles associated with the middle bus, portions of the latter being shaped to form center contacts for said receptacles, two receptacles, one adapted to be associated with each of the outside buses, switches to connect said latter receptacles to their associated buses, integral members constituting the center contacts of each of the outside receptacles and one pole of said switches, and conducting members secured to each of the outside buses and provided with a portion constituting the other pole of said switches.

10. An interchangeable panel-board section adapted for the derivation of two branch circuits therefrom comprising an insulating base, substantially parallel buses associated with said base, two receptacles associated with the middle bus, portions of the latter being shaped to form center contacts for said receptacles, two receptacles, one adapted to be associated with each of the outside buses, switches to connect said latter receptacles to their associated buses, integral

members constituting the center contacts of each of the outside receptacles and one pole of said switches, conducting members secured to each of the outside buses and provided with a portion constituting the other pole of said switches, and an insulating cap to receive said receptacles and recessed to provide a protective covering for said switch, operation of the latter being permitted when said cap is in normal position, whereby a dead-front interchangeable panel section is formed.

11. An interchangeable panel board section adapted for the derivation of two branch circuits therefrom comprising an insulating base, three substantially parallel bus-bars associated with said base, receptacles positioned over and connected to the middle one of said bars, receptacles positioned over and adapted to be connected to each of the outside of said bars, switches also positioned over and connected to said outside bars whereby said connection of the last named receptacles to their associated bars may be effected, and means forming channels extending between the switches and the receptacles positioned over the outside buses, and a branch circuit lead positioned in said channel and connected to a receptacle positioned over said middle bus.

In witness whereof, I have hereunto subscribed my name.

REUBEN B. BENJAMIN.
